UNITED STATES PATENT OFFICE.

WILLIAM TUNNESSEN, OF HAZLETON, PENNSYLVANIA.

MINER'S LAMP.

No. 888,768.

Specification of Letters Patent.

Patented May 26, 1908.

Application filed May 3, 1907. Serial No. 371,605.

To all whom it may concern:

Be it known that I, WILLIAM TUNNESSEN, a citizen of the United States, residing at Hazleton, in the county of Luzerne and 5 State of Pennsylvania, have invented a new and useful Improvement in a Miner's Lamp, of which the following is a specification.

This invention relates to certain new and useful improvements in miners' lamps and 10 more particularly to the neck and cap of the same, the object being to form a hinge for the cap without the use of solder.

Another object of my invention is to provide the lamp with a metal neck having an 15 integral tongue which is bent back upon itself over the pintle of the cap so as to form a hinge without any danger of it being melted off by the heat of the torch of the lamp.

With these and other objects in view, the 20 invention consists in the novel features of construction, combination and arrangement of parts hereinafter fully described and pointed out in the claims.

In the drawings forming a part of this 25 specification:—Figure 1 is a side view of my improved miner's lamp. Fig. 2 is a vertical sectional view of the same, Fig. 3 is a top plan view of the neck and cap detached from the lamp, showing the manner of hinging the cap 30 to the neck.

In the drawing A indicates the tank of an ordinary miner's lamp which is provided with the usual spout in which the wick is placed, and the ordinary hook by which it is 35 secured on the cap of the miner.

The tank is provided with an open flanged top in which is secured the lower flanged portion of a neck B which is formed of any suitable metal, and is provided with an outwardly projecting tongue C which is bent 40 back upon itself around one of the parallel bars of a link D. Secured around the other parallel bar of the link is the tongue E' of the flanged cap E, which is securely crimped

around the same, so that when the cap is 45 thrown up off the neck, it will not drop down on the tank.

It will be seen by fastening this member of the link to the cap, the other member will form a pintle so that the cap can readily be 50 swung over the neck or off the same, and one which is so constructed that the cap will not be hurt by the blaze of the torch.

The neck is secured in the tank by crimping the lower edge of the same to the edge of 55 the tank, so that the usual solder is dispensed with, thereby overcoming the difficulties now existing in miners' lamps of this character of the neck being melted off the tank by the blaze of the torch. It will also be 60 readily seen that by providing the neck with an integral tongue, the pintle of the link carried by the cap will be securely mounted on the same without any danger of it being melted off. 65

Having thus fully described my invention, what I claim as new and desire to secure by Letters Patent is:—

1. A miner's lamp, comprising a tank and a neck portion crimped thereto, said neck 70 having a laterally extending integral tongue, said tongue being bent to form a sleeve, a cover fitting said neck and having an integral tongue extending above and parallel to the tongue of the neck when the cover is closed, 75 said tongue being also bent to form a sleeve, and a link having its opposite side members in engagement with said sleeves, respectively.

2. A miner's lamp, having a neck portion 80 crimped and secured in the lamp body, an integral tongue carried by said neck, a cover, a tongue formed integral with the cover, and a link connecting said tongues.

WILLIAM TUNNESSEN.
